(57) **CLAIM**

The ornamental design for a hook element piece for hook-and-loop fastener, as shown and described.

DESCRIPTION

FIG. 1 is a front view of a hook element piece for a hook-and-loop fastener.

FIG. 2 is a top plan view of the hook element piece of FIG. 1.

FIG. 3 is a right side view of the hook element piece of FIG. 1.

FIG. 4 is a base view of the hook element piece of FIG. 1. FIG. 5 is a cross-sectional view taken on line 5—5 of FIG. 2; and,

FIG. 6 is a fragmentary perspective view of the hook element piece of FIG. 1.

The claimed design is shown fragmented for ease of illustration and clarity of the disclosure.
